United States Patent Office

Des. 183,325
Patented Aug. 5, 1958

183,325

BROACH OR SIMILAR ARTICLE

Hilda Scott Rogan, Buffalo, N. Y.

Application July 10, 1957, Serial No. 46,890

Term of patent 14 years

(Cl. D45—19)

FIG. 1

FIG. 2

Fig. 1 is a plan view of a brooch or similar article, showing my new design.

Fig. 2 is a sectional view taken along line II—II of Fig. 1.

The dominant features of my design reside in the portion shown in full lines.

I claim:

The ornamental design for a brooch or similar article, as shown and described.
